UNITED STATES PATENT OFFICE

153,014

DESIGN FOR A PIPE WORKING MACHINE

Robert B. Pealer, Garrettsville, Ohio, assignor to
Beaver Pipe Tools, Inc., Warren, Ohio, a cor-
poration of Ohio

Application October 3, 1946, Serial No. 133,717

Term of patent 14 years

(Cl. D54—14)

To all whom it may concern:

Be it known that I, Robert B. Pealer, a citizen of the United States of America, residing at Garrettsville, county of Portage, State of Ohio, have invented a new, original, and ornamental Design for a Pipe Working Machine, of which the following is a specification, reference being had to the accompanying drawings, forming a part thereof:

In the drawings, Fig. 1 is a perspective view of a pipe working machine embodying my new design, looking from a position adjacent the front left corner with the tool carrier in a withdrawn position remote from the work chuck; Fig. 2 is the rear elevation of a machine with the tool carrier in an active position adjacent the work

chuck; Fig. 3 is an elevation looking at the right hand end of the machine, and Fig. 4 is an elevation looking at the left hand end.

I claim:

The ornamental design for a pipe working machine, as shown.

ROBERT B. PEALER.
